(57) CLAIM

The ornamental design for a ladies swimwear garment, as shown and described.

DESCRIPTION

FIG. 1 is a front view of an embodiment of the ladies swimwear garment;

FIG. 2 is a rear view thereof;

FIG. 3 is a front view of an embodiment of the ladies swimwear garment;

FIG. 4 is a rear view thereof;

FIG. 5 is a front view of an embodiment of the ladies swimwear garment; and,

FIG. 6 is a rear view thereof.

The broken lines shown in the drawings illustrate portions of the ladies swimwear garment and form no part of the claimed design.
